UNITED STATES PATENT OFFICE.

CONRAD KEMPF, OF NUERMBERG, GERMANY, ASSIGNOR TO SUDDEUTSCHE CHRIST-
BAUMSCHMUCK-U REFLEKTOREN GESELLSCHAFT MIT BESCHRANKTER HAFTUNG,
OF NUERMBERG, GERMANY.

DESIGN FOR A REFLECTOR FOR CHRISTMAS-TREE DECORATION.

Application filed December 2, 1926. Serial No. 19,906. Term of patent 3½ years.

To all whom it may concern:

Be it known that I, CONRAD KEMPF, a citizen of the German Republic, residing at Nuremberg, in the country of Germany, have invented a new, original, and ornamental Design for a Reflector for Christmas-Tree Decoration, of which the following is a specification, reference being had to the accompanying drawing, forming part thereof.

Figure 1 is a plan view and Figure 2 is an elevation view of a reflector for Christmas tree decoration, showing my new design.

I claim:
The ornamental design for a reflector for Christmas tree decoration as shown.

CONRAD KEMPF.
